UNITED STATES PATENT OFFICE.

NATHAN PAINE, OF OSHKOSH, WISCONSIN.

DOOR CONSTRUCTION.

Application filed October 7, 1921. Serial No. 506,142.

To all whom it may concern:

Be it known that I, NATHAN PAINE, a citizen of the United States, and resident of Oshkosh, in the county of Winnebago and State of Wisconsin, have invented new and useful Improvements in Door Constructions, of which the following is a description, reference being had to the accompanying drawings, which are a part of this specification.

This invention has for its object to provide a door with a miter joint that can be manufactured by a machine operation and that will produce a tight joint on both sides.

In the manufacture of doors and the like very desirable ornamental effects may be produced by forming a mitered frame between the panel and the outside frame, but heretofore the difficulty of making such mitered frame with tight joints on opposite faces has made such a door practically impossible as a machine-made product and consequently doors of this character have only been made as fine examples of the cabinet-maker's art and, being of hand work, have been too expensive for ordinary building purposes.

The present invention, however, provides a door with a mitered joint that can be readily made in an ordinary end-matching machine and that will have tight fitting joints formed in the opposite faces so as to present an equally neat and ornamental appearance on both sides of the door.

With the above and other objects in view the invention consists in the door with a miter joint as herein claimed and all equivalents.

Referring to the accompanying drawings, in which like characters of reference indicate the same parts in different views,

Figure 1 is a face view of one corner of a door with an inner frame having a miter joint of this invention;

Figure 2 is a sectional view thereof;

Figure 3 is a view looking at the corner of the inner frame in line with the miter joint, and

Figure 4 is a similar view with the members of the inner frame separated.

In these drawings, 10 indicates the door outer frame, the parts of which may be

mortised and doweled as usual, while 11 represents the inner frame, having a tongue 12 fitting in the groove of the outer frame. The parts of the inner frame 11 are mitered together and enclose a panel 13, which fits in a groove 14 at the molded inner edge thereof, there being a fillet of molding 15 along the shoulder formed between the inner frame and the thicker outer frame.

In making the miter joint both ends are formed alike with a surface 16 normal to the opposite faces thereof except for a projecting tongue 17 parallel with the faces and a groove 18 with one wall in continuation of the side of the tongue. When fitted together the tongue 17 of each end fits within the groove 18 of the other and, as the two ends are exactly alike with their respective tongues and grooves at the same distances from their opposite faces, they fit together in such a way that said opposite faces of both ends are flush and meet with a true tight joint. This operation of cutting the tongue and groove for the miter joint may be performed on the ordinary end-matching machine with the work gage set at an angle of 45° with relation to the line of travel of the work and, as the operation is the same for both ends of each piece, it constitutes a simple mill operation that does not materially increase the cost of manufacturing the door. The ornamental appearance of the mitered inner frame, however, adds greatly to the value of the door.

While the invention is particularly applicable to doors for buildings, it is also suitable for other door and panel structures.

What I claim as new and desire to secure by Letters Patent is:

A door comprising an outer frame, an inner frame having a tongue and groove connection therewith and formed of strips mitered together, said inner frame being of material considerably thinner than the outer frame whereby projecting shoulders are produced, molding strips forming fillets along the shoulders, the inner edges of the strips forming the inner frame being molded and grooved, and a panel fitting in the groove thereof.

In testimony whereof I affix my signature. 105
NATHAN PAINE.
